UNITED STATES PATENT OFFICE.

ALEXANDER V. JENSEN, OF BROOKLYN, NEW YORK, ASSIGNOR TO HIMSELF AND
IVAN E. A. KONIGSBERG, OF NEW YORK, N. Y.

KEY-DUPLICATING MACHINE.

1,081,949.

Specification of Letters Patent.

Patented Feb. 24, 1914.

Application filed March 31, 1913. Serial No. 757,844.

To all whom it may concern:

Be it known that I, ALEXANDER V. JENSEN, a citizen of the Danish Monarchy, and a resident of Brooklyn, Kings county, New York, have invented certain new and useful Improvements in Key-Duplicating Machines, of which the following is a specification.

This invention relates to key duplicating machines and the object of the invention is to provide a simple and easily operated machine for duplicating keys for use with pin tumbler locks or other types of locks operated with flat keys, or keys characterized by being provided with one or more cuts or notches in certain combinations and which are all well known.

Other objects of the invention will appear as this specification proceeds while reference is had to the accompanying drawings illustrating the invention and in which—

Figure 1 is a plan view of a key duplicating machine embodying my invention. Fig. 2 is an end elevation looking in direction of arrow 2 Fig. 1. Fig. 3 is an end elevation looking in the direction of the arrow 3 in Fig. 1. Fig. 4 is a front view looking in the direction of arrow 4 in Fig. 1, and Fig. 5 is a detail view.

The reference numeral 5 denotes a suitable base provided with the two standards 6 and 7.

8 is a main driving shaft journaled in the standards and centrally on said shaft there is secured by any suitable means a cutter or rotary file 9. The shaft 8 carries a pinion 10 with which meshes a gear 11 on a shaft 12 to which is secured the operating handle 13 by means of which the cutter is driven.

14 is a key carrying slide or supporting means. It comprises a central internally threaded boss 15 and a forward and a rear arm 16 and 17 each of which is provided with a key receiving socket or cutout 18 for the pattern key and the key blank.

19 are clamping screws to clamp the keys to the slide 14.

20 is a handle on the slide.

21 is an endless screw journaled in the standards 6 and 7 but secured against axial movement by any suitable means. The screw 21 passes through and is in threaded engagement with the aforesaid threaded boss 15, so that when the screw is rotated, the slide 14 is moved transversely of the machine as will

be understood. The screw 21 is rotated from the shaft 12 through the instrumentalities of the pinion 22 on said shaft and the gear 23 secured to the screw adjacent the standards 7.

Means, however, are provided for rotating the endless screw independently of the rotation of the shaft 8 by a handle 24 fast in the gear 23. To this end I have provided a clutch 25 in which a pin 26 may be engaged or disengaged from an aperture 27 in the pinion 22 which is loose on the shaft 12 while the clutch is fast on said shaft. When the pin 26 is disengaged from the pinion, the endless screw may be turned by hand by the handle 24. When the pin 26 engages the aperture 27 the pinion 22 is clutched to the shaft and revolves with it. In the base of the machine is suitably mounted a gage pin 28 which may be adjusted vertically and locked in position by a nut 29.

In operation the slide 14 is moved to the one side and the pattern key 30 is clamped in the socket 18 above the gage pin and the key blank 31 is clamped in the socket 18 under the cutter 9. The gage pin is adjusted so as to touch the highest point on the pattern key at which the bitting in the key commence. This point is indicated at 32 in Fig. 4. The key blank is clamped in a position similar to that of the pattern key but with its bitting edge upward against the cutter. It will also be noted that the sides 35 and 36 at the ends of the arms 16 and 17 act as stops for the shoulders 37 of the keys, whereby it is possible to place the keys in exact similar positions transversely of the slide 14 at its opposite ends. When the clutch is in and the shaft 12 is rotated the slide 14 with the two keys is fed past the cutter and the gage pin. By pressing yieldingly on the handle 20 the operator forces the key blank up against the cutter to cut a notch of exactly the same size, depth and curvature as the notch in the pattern key which at the moment is above the gage pin. If desired a weight 40 may be placed on the handle 20 to tip the slide 14 up against the cutter 9. If desired, the pinion 22 may be unclutched from the shaft 12 and the endless feed screw operated at any desired speed by the operator to feed the keys past the cutter.

From the foregoing it will be apparent that the slide 14 constitutes a key carrying

and key supporting member having a transverse movement past the cutter and a rocking movement on the screw and toward and away from the cutter. Further, that it is within the power of the operator to either feed the keys continuously or intermittently past the cutter, or transversely intermittently, but continuously with relation to the cutting action of the cutter. Or the operator may combine these movements and feed the keys past and toward the cutter at a speed directly suited to the bittings or notches to be duplicated.

Where a key of the character shown in Fig. 5 is to be duplicated, I prefer a cutter 45 of the form shown in said figure, and it will be seen that by means of the movements of the slide referred to, the operator is able to reproduce a deep cut in the key by leaving the slide 14 immovable transversely until the desired depth has been reached as controlled by a gage pin of suitable shape.

Various changes in the detailed construction as here described and illustrated may be made within the principle and scope of the invention and I do not limit myself otherwise than as expressed in the appended claims.

I claim:

1. In a key duplicating machine the combination of a base, standards arising from the same, an endless screw journaled in said

standards, a gage pin adjustably secured in said base on one side of said endless screw, a cutter supported in said standards on the other side of said endless screw, a slide mounted on the latter and in threaded engagement therewith, means for supporting a key and a key blank in said slide at the opposite ends thereof, means for tipping said slide to force the key into contact with the said gage pin and the key blank into contact with said cutter, and means for simultaneously rotating the cutter and the endless screw to move said slide transversely of the cutter and the gage pin.

2. In a key duplicating machine the combination of supporting means for a key and a key blank, a gage pin, means for adjusting the same, a cutter, means for rotating said cutter, mechanism actuated by said rotating means for automatically moving the said supporting means transversely of the said gage pin and cutter and means for vertically oscillating said supporting means to force the key into contact with said gage pin and the key blank into contact with the said cutter.

Signed at Independence, Mo., this 24th day of March, 1913.

ALEXANDER V. JENSEN.
